UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FOLDING SEAT.

1,348,375.

Specification of Letters Patent. Patented Aug. 3, 1920.

Application filed March 4, 1920. Serial No. 363,230.

To all whom it may concern:

Be it known that I, ALONZO E. RHOADES, a citizen of the United States, residing at Hopedale, county of Worcester, State of

5 Massachusetts, have invented an Improvement in Folding Seats, of which the following description, in connection with the accompanying drawing, is a specification, like characters on the drawing representing

10 like parts.

This invention relates to improvements in folding seats especially designed for spoolers, spinning frames, looms, or other similar machines and the object thereof is to provide

15 a seat of this type which when in open position will stand in a horizontal plane projecting beyond the end of the machine frame and which when in closed position will stand in a substantially vertical position parallel

20 to or close against the front or back of the machine and to provide a movable connection between the seat and its attaching bracket which will directly control or effect the movement of the seat between such an

25 open and such a closed position.

It is usually desirable that such folding seats which are used by the operatives chiefly for rest shall occupy as little space as possible and shall when in closed position allow

30 free passage for the operatives between closely adjacent machines. It is also usually desirable that such seats shall either automatically move to closed position or remain in open position according to the desires of

35 the particular operatives.

The present invention presents a seat which when in open position extends beyond the end of the frame of the machine enabling the operative to sit in the space between adjacent machines and which is movable to a closed position up against the front or back of the machine.

40 It is the object of the invention further to provide a simple and strong construction of seat embodying the desired characteristics which may be readily applied to existing machines.

45 These and other objects and features of the invention will appear more fully from the accompanying description and drawings and will be particularly pointed out in the claims.

In the drawings—

50 Figure 1 is a side elevation partially

broken away of a folding seat and supporting bracket embodying the invention illustrating the same as attached to a portion of a machine frame.

55 Fig. 2 is a plan view of the construction shown in Fig. 1.

60 Fig. 3 is a detail in cross section taken on the line 3—3 of Fig. 2.

65 While the invention is particularly adapted for textile machinery it is obviously useful in connection with any machine or structure in which it is desirable to have a movable seat which can be placed in horizontal or operative open position and which when not in use is folded to a substantially vertical or inoperative position at the front 70 or back of the machine.

75 The aisles between the rows of textile machines running in both directions are made as narrow as possible and it is therefore desirable that such a seat shall fold as closely against the machine frame as possible when not in use.

80 Some operatives prefer that the loom seat shall be automatically thrown into inoperative position when released, while other operatives prefer to have the loom seat normally remain in horizontal operative position but also be capable of being released to and retained in inoperative position when the operative leaves the seat. In this respect the present invention preferably makes use of means similar to those described in my Patent No. 1,329,546, granted February 3, 1920. In the preferred embodiment of 85 the invention disclosed herein the seat is supported upon the frame 1 by a two part bracket consisting of the sections 2 and 3 which are clamped upon the frame by a bolt 4, one or both of said sections preferably having extensions or lugs 5 embracing the 90 flange at the edge of the frame. The section 2 of the bracket which in this instance is shown at the front of the frame 1 is provided at the front of the frame with a vertically extended boss or socket 6. 95

100 A support is mounted for vertical rotation in this boss 6 and is shown as a stud 7 seated in the boss and having a head 8 resting on the top of the boss. The stud 7 is held in place by a cotter pin 9 and a washer 105 10 at the lower end.

110 A horizontal stud 11 is rigidly mounted in the head 8 and projects at right angles to

the support or stud 7. The seat 12 is preferably of the usual circular type and is provided with an arm 13 extending substantially radially therefrom and also substantially in the plane of the seat. This arm 13 is provided with a laterally extending integral sleeve 14 fitting over the stud 11. The open or horizontal position of the seat is determined by coöperating stops on the 10 arm 13 and the bracket. For this purpose a stop 15 is shown extending laterally from the arm 13 contacting with the stop 16 extending from the bracket.

A helical spring 17 surrounds the sleeve 15 14 and is anchored at one end 18 in the arm 13 and at the other end 19 in a collar 20 rotatably mounted upon the stud 11. The collar 20 preferably is provided with a polygonal extension 21 enabling it to be grasped 20 by a wrench for the adjustment of the attachment of the spring. The stud 11 is provided with a plurality of transverse apertures 22 adapted to receive the cotter pin 23 and the collar 20 is preferably provided 25 with a larger number of apertures 24 to receive the cotter pin so that the collar may be adjusted to cause any one of these apertures to come into alinement with either of the apertures 22 through the stud. By reason 30 of this adjustment any desired tension may be placed upon the helical spring 17 so that the tension of the spring may be made just sufficient to retain the seat in substantially vertical or inoperative position when raised 35 to such position by the operative or the tension of the spring may be increased sufficiently to throw the seat immediately to the substantially vertical or inoperative position when it is released by the operative, all as 40 more fully set forth in my aforesaid patent.

Suitable connections are provided between the support 7 which rotates on a vertical axis and the socket portion 6 of the bracket to cause the support to rotate about its vertical 45 axis when the seat is swung about the horizontal axis of the stud 11. As a simple and preferred construction for effecting this end a gearing connection is illustrated. This gearing connection is shown as a series of 50 radial pins 25 projecting from the boss 6 and corresponding gear teeth 26 formed on a flange extending substantially in the plane of the arm 13.

It will thus be seen that as the seat is 55 swung about the stud 11 from its open or operative position shown in full lines in the drawing to its closed vertical or inoperative position that this gearing connection will cause the support 7 to rotate about its vertical axis swinging the stud 11 into parallelism with the front of the frame as shown in dotted lines in Fig. 2 and bringing the seat into vertical position parallel with and against the front of the frame. It will also 60 be seen that when the seat is moved from its

vertical or inoperative position to its horizontal or operative position the reverse movement takes place.

The movement of the seat into its vertical or inoperative position is limited by the contact of the seat or some part connected thereto with the machine frame or some part connected thereto or by coöperating stops on the two parts. Such stops are shown in the drawing at 27 on the arm 13 and 28 on 75 the bracket.

The seat in its movement between open and closed positions therefore has a compound vertical and horizontal swinging movement. When the seat is in open position it extends out beyond the end of the frame with the seat standing in a horizontal plane and with the arm 13 standing in a vertical plane which is parallel to but not normal to the vertical plane of the front or back 80 of the machine frame. When the seat has moved to its closed or inoperative position the plane of the seat stands in a substantially vertical plane parallel to or inclined to the vertical plane of the machine frame. 90

It will thus be seen that a simple and efficient structure of seat is provided which occupies the minimum amount of space which enables the seat to extend out beyond the end of the frame and which causes the seat 95 when in closed or inoperative position to rest snugly against the front or back of the machine frame.

Having thus described my invention what I claim as new and desire to secure by Letters Patent is— 100

1. A folding seat comprising a bracket and means for attaching it to a machine frame, a support mounted in the bracket for rotation about a vertical axis, a seat provided with an arm mounted on the support for rotation about a horizontal axis, and gearing connections between the arm and the bracket acting upon rotation of the arm to effect the rotation of the support. 110

2. A folding seat comprising the construction defined in claim 1 together with co-operating stops on the arm and bracket to limit the downward rotation of the arm and to position the seat for occupancy. 115

3. A folding seat comprising a bracket and means for attaching it to a machine frame, a seat provided with an arm, and connections between the said arm and bracket acting to effect the movement of the seat between open horizontal position and closed vertical position against the front or back of the frame by a compound vertical and horizontal swinging movement. 120

4. A folding seat comprising a bracket 125 and means for attaching it to a machine frame, a seat provided with an arm, a movable connection between the end of the arm and the bracket acting to direct the movement of the seat between an open position 130

in a horizontal plane and a closed position in a substantially vertical plane against the front or back of the machine frame.

5. A folding seat comprising a bracket and means for attaching it to a machine frame, a seat provided with an arm extending substantially radially and substantially in the plane of the seat, a movable connection between the end of the arm and the bracket acting to direct the movement of the seat between an open position in a horizontal plane and a closed position in a vertical plane substantially parallel to the arm when in open position.
- 10 15 6. A folding seat comprising a bracket and means for attaching it to a machine frame, a support mounted in the bracket for

rotation about a vertical axis, a stud extending horizontally from the support, a seat provided with an arm mounted for horizontal rotation on the stud, gearing connections between the arm and the bracket acting upon rotation of the arm to effect the rotation of the support. 20

7. A folding seat comprising the construction defined in claim 6 in which the said carrying connection comprises a plurality of pins extending radially from the bracket and intermeshing gear teeth projecting from the arm. 25

In testimony whereof, I have signed my name to this specification.

ALONZO E. RHOADES.
